Patented Dec. 31, 1918.

FIG. 1.

INVENTOR
Elmer Walters

BY
A. Winslow Wheatley
ATTORNEY

UNITED STATES PATENT OFFICE.

ELMER WALTERS, OF ELDORADO, KANSAS.

HYDROCARBON-BURNER.

1,289,327.

Specification of Letters Patent. Patented Dec. 31, 1918.

Application filed August 14, 1918. Serial No. 249,902.

To all whom it may concern:

Be it known that I, ELMER WALTERS, a citizen of the United States, residing at Eldorado, in the county of Butler and State 5 of Kansas, have invented a new and Improved Hydrocarbon-Burner, of which the following is a specification.

This invention has reference to that type of oil burners more particularly adapted 10 for use on steam boilers and which are mounted on the boiler for being projected into the combustion chamber of the boiler with the torch or nozzle end positioned for directing the flame against the fire-wall of 15 the said chamber.

Primarily, my invention seeks to provide a burner of the general type stated of a simple and economical construction, that has provision for being readily attached to and 20 for projecting it through the boiler and in which means are included for a thorough intermixing of the oil and air and drawing the mixed gas, under a forced steam jet feed, to the ignition or nose end of the burner.

With other objects in view that will hereinafter appear, my invention is an improved oil burner that embodies the peculiar features of construction and novel arrangement 30 of the parts to be hereinafter described in detail, specifically pointed out in the appended claims and illustrated in the accompanying drawings, in which:

Figure 1 is a longitudinal section of my improved burner, so much of a boiler being 35 shown as is necessary to illustrate a practical application of my invention.

Fig. 2 is a plan view of the burner, the boiler wall being shown in horizontal section.

Fig. 3 is a perspective view of a burner constructed in accordance with my invention.

Fig. 4 is a transverse section thereof on the line 4—4 on Fig. 2.

Fig. 5 is a detail perspective view that shows the outer or tubular body with its gas and oil infeed lateral.

Fig. 6 is a perspective view of the inside or steam jet pipe.

My improved construction of burner embodies a main or body portion 2 that includes a tubular member 1, one end of which terminates in a tapered or restricted portion 2, the purpose of which will presently appear and which merges with a forwardly extending nozzle 3 of uniform diameter and

which terminates in a tapering nose or ejector end 4.

At the other end, the body 1 is internally threaded, as at 5, to receive the externally 60 threaded portion 6 of an injector pipe 7 that projects within the tapered end of the body or casing 1, as is clearly shown in Fig. 1.

In the drawings, the several parts, as shown, are proportioned as follows:

The steam feed or ejector pipe extends six inches within the body, the latter being two inches in diameter and the ejector tube one and one-half inches in diameter.

By making the ejector or steam pipe of 70 nearly the diameter of the outer or tubular body 1, the fuel (mixed air and gas), is drawn along a restricted passage and in contact with a large surface presented by the steam pipe and, by reason thereof, the 75 vaporization of the fuel is much facilitated, since by heating the burner nozzle internally through radiation from the steam pipe, as it is externally heated in the boiler fire-chamber, the fuel vaporization is maintained 80 under a uniform and perfect condition.

The outer end 8 of the ejector pipe is threaded for connection with one of the threaded tubes 9 of a T-coupling, the other 85 end of which is normally closed by a screw plug 10.

11 designates a steam feed pipe that connects with the T-coupling, as shown.

The burner body 1 is cast with tubular laterals 12—13 and to provide for connecting the air and gas and oil feed pipes to either side of the burner, the latter has a set of oil and gas laterals, at each side, as shown, it being understood that, when the laterals 12—13, at one side are being used, 95 the laterals, at the other side, are closed by screw plugs 14—14.

In practice the oil inlet 12 is of larger diameter than that of the oil inlet, the two diameters in the form of my burner shown 100 being one and one-fourth inches for the air inlet and one inch for the oil inlet.

In the practical application of my burner, an opening of the diameter of the nozzle is made in the boiler wall and at such point that the flame from the burner is ejected against the fire-wall 16 of the fire-chamber 17, it being understood that a substantially tight connection of the burner with the body wall is provided for by forcing the tapered portion of the burner into and upsetting the wall opening 18, as best shown in Fig. 1.

From the foregoing description taken in connection with the drawings, the complete construction, the advantages and the manner of the application of my invention will be 5 readily apparent to those skilled in the art to which my said invention relates.

What I claim is:

1. A burner of the type stated comprising a tubular body internally threaded at one 10 end and whose other end terminates in an ejecting nozzle, a pair of laterals that communicate with the tubular body, means for connecting said laterals with air and gas feed pipes, a steam nozzle that includes an externally threaded hub portion for threading 15 into the threaded end of the tubular body and a tapering ejecting nose that extends into the nozzle end of the tubular casing, the said hub portion of the steam nozzle having 20 an outwardly projected extension adapted

to receive a union coupling for connecting the nozzle with a steam feed pipe.

2. A burner of the type stated comprising a tubular body internally threaded at one 25 end and whose other end terminates in an ejecting nozzle, pairs of oppositely projected tubular laterals that communicate with the tubular body, means for connecting adjacent pairs of the said laterals with air and gas feed pipes, a steam nozzle that 30 includes an externally threaded hub portion for threading into the threaded end of the tubular body and a tapering ejecting end that extends into the nozzle end of the tubular casing, the said hub portion of the steam nozzle including an outwardly projected tubular extension threaded to receive a union 35 coupling for connecting the nozzle with a steam feed pipe.

ELMER WALTERS.
